BLANK FEEDING MECHANISM

Justin Simpson, Mount Healthy, Ohio, assignor to
 American Can Company, New York, N. Y., a
 corporation of New Jersey

Application July 15, 1939, Serial No. 284,786

7 Claims. (Cl. 271—44)

The present invention relates to a blank feeding mechanism such as is used in container or can making machinery and the like and has particular reference to controlling the feeding of the blanks while the machine, on which the feed mechanism is used, continues to operate without interruption.

In the manufacture of container parts made of fibre or the like where succeeding operations are performed in a continuing process and in a single machine, it is often desirable to temporarily stop the feeding of new blanks into the machine but at the same time to continue other operations of the machine. This is particularly desirable where certain steps in the operations on the articles require an application of heat. For example where fibre containers are being made, stoppage of the blanks or partially made container parts while under heat treatment, would result in severe scorching or burning of the articles and not only damage such beyond use but would thereby set up a fire hazard.

The present invention contemplates overcoming this difficulty by providing a blank feed which may be stopped from feeding new blanks into the machine while the machine continues to operate so that any partially formed containers will continue through the subsequent operations.

An object therefore of the invention is the provision of a blank feeding mechanism for a can making machine wherein the feeding of new blanks into the machine may be stopped without stopping the operation of the machine.

Another object is the provision of such a feeding mechanism wherein new blanks, normally to be fed into the machine, are shifted out of the path of travel of the feeding mechanism when it is desired to prevent feeding of the blanks, thus permitting continued operation of the feeding mechanism with other operations of the machine but without feeding new blanks, this abnormal phase being under full control, and maintained as long as desired.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a blank feeding mechanism embodying the instant invention, with parts broken away;

Fig. 2 is a longitudinal section taken substantially along the line 2—2 in Fig. 1, with parts broken away;

Fig. 3 is a longitudinal section taken substantially along the line 3—3 in Fig. 1, with parts broken away;

Fig. 4 is a transverse section taken substantially along the line 4—4 in Fig. 1, with parts broken away; and

Figs. 5, 6 and 7 are views similar to Fig. 3 and showing the movable parts of the mechanism in different positions.

As a preferred embodiment of the instant invention, the drawings illustrate a feeding mechanism adapted to feed individual fibre can body blanks A from a magazine B (Figs. 1 and 2) and carry them forward into the grip of a pair of feed rollers C for advancement into and through a can body forming machine or the like. The feeding mechanism is preferably supported in a frame 11 (Figs. 1 and 2) which may be a part of the forming machine.

The magazine B includes a plurality of vertically disposed rods 13 secured to a horizontal table 14 bolted to the machine frame 11. The bars are arranged to retain in position a stack of the blanks A. The blanks are supported above the table on laterally projecting lugs 17 formed on the magazine bars 13 and also on a pair of inclined rails 18 which are secured to the top of the table.

The blank advancing or feed rollers C are disposed adjacent that side of the magazine having the inclined bars 18. These rollers are mounted on transverse shafts 21 which are carried in bearings 22 provided in upright brackets 23 formed integrally with the table 14. These rollers are rotated in unison in any suitable manner in time with the other operating parts of the machine. The rollers are located one above the other so that a blank A fed horizontally from the bottom of the stack in the magazine will readily enter between the rollers and will thus be advanced or fed by them.

A cross-bar 25 formed as an integral part of the brackets 23 extends transversely of the table 14 and supports the two magazine bars 13 along this side of the magazine. These two bars extend down just far enough to prevent blanks, except the lowermost one, from shifting out of the magazine when the lowermost blank is fed into the rollers C.

Feeding of the blanks A from the magazine is preferably effected by a sliding and reciprocating feed bar 31 (Figs. 1 and 2) which slides toward and away from the magazine in a slideway 32 formed in a guide block 33 bolted to the top of the table. A plate 34 confines the slide bar in its

slideway. The inner end of the slide bar is beveled as at 38 to facilitate passage of the bar under the lowermost blank in the magazine. Adjacent this beveled end there is disposed a fixed feed dog 37 set into a recess in the bar and bolted in place. This dog engages the rear edge of the lowermost blank in the magazine and feeds it forward into the rollers C, when the feed bar moves on a forward or feeding stroke.

10 Reciprocation of the feed bar on its forward and return strokes is brought about by an actuating arm 41 which is mounted on a pivot pin 42 carried in the frame 11. One end of the arm is formed with a segment gear 43 and this end

15 extends up through openings 44, 45 formed respectively in the frame 11 and in the table 14 and guide block 33 and meshes with a rack 47 formed on the bottom of the slide bar 31. The opposite end of the arm is connected to a link

20 48 which leads to any suitable moving part of the machine. The arm is thus actuated in time with the other moving parts of the machine.

Feeding of the blanks from the magazine B is controlled by a device which includes a stack 25 lifting instrumentality comprising a pair of spaced and parallel arms 51 (Figs. 1, 3 and 4) which are formed on a hub 52 mounted on a pivot shaft 53 carried in bearing lugs 54 projecting up from the table 14. These arms are 30 disposed one on each side of the feed bar 31 and the forward free ends of the arms extend under the stack of blanks A retained in the magazine B. Intermediate its length, one of the lifter arms 51 carries a cam roller 56 which operates on a 35 cam surface 57 of a movable cam block 58. This cam surface is provided with a depressed section and a raised section.

Hence when the cam roller 56 is on the depressed section of the cam surface 57, as shown 40 in Fig. 3, the lifter arms 51 are maintained with their inner ends, which extend under the stack of blanks A, below and clear of the blanks. In such position they will not interfere with feeding of the blanks from the magazine.

45 However, when the cam roller is on the raised section of the cam surface the inner ends of the lifter arms 51 engage under the stack of blanks A and raise them in the magazine, holding them above the path of travel of the reciprocating feed 50 bar. In this raised position, the feed dog 37 passes under the stack without engaging and without feeding a blank therefrom. However, the feed bar continues to reciprocate with the rest of the machine but no new blanks will be 55 fed forward as long as such abnormal feed condition obtains.

Shifting of the cam roller 56 on the cam surface 57 of the cam block 58 is brought about by moving the cam block under the roller. For this 60 purpose the cam block is supported on top of the table 14 and is formed with laterally extending side tongues 61 (Fig. 4) which are frictionally confined between a gib 62 on one side formed integrally with the guide blocks 33 and a parallel 65 gib 63 on the other side which is bolted to the table.

Movement of the cam block 58 between its gib 70 is effected by an actuating finger 65 which travels with the feed bar 31. The finger is carried on a pivot stud 66 which extends through a slot 67 formed in the guide block 33 and which is threaded into a side of the feed bar. The free end of the finger has a depending hook 68 which operates in a slot 69 provided in the cam block. 75 Inside the slot the cam block is formed with a

shoulder 71 and a lug 72 which alternately co-operate with the finger hook in shifting the cam block forward and back.

Intermediate the length of the actuating finger 65, it is connected to the upper end of a depending link 74. This link extends down through openings 75, 76 formed respectively in the table 14 and the frame 11. At its lower end the link is secured to a movable core 78 (see also Fig. 6) of an electric solenoid 79 secured to a bracket 10 81 bolted to the frame 11. The core is normally maintained energized for normal feeding by electric circuits shown in the wiring diagram in Fig. 3.

As is usual in solenoids of this type a spring 15 83 is located inside of the solenoid casing surrounding a reduced upper end of the core 78. This spring is held under compression when the solenoid is energized and when the core is raised. However, when de-energized the spring 83 acts 20 to pull or force the solenoid core into the solenoid. In the present construction of parts the spring is assisted by the weight of the link 74 and the finger 65 which when not held up fall into the lower positions.

25 In the wiring diagram there is shown a generator 85 which is indicative of the source of supply of electric energy. One side of the generator is connected by a wire 86 to the solenoid. The other side of the generator is connected by a wire 87 to a normally closed feed stop switch 88. This switch is connected by a wire 89 to the solenoid. Hence when the stop switch is closed the circuit is complete and energy from the generator flows through the solenoid. This flow of 35 energy is interrupted only when the stop switch is mechanically opened to stop feeding of blanks from the magazine.

Under normal operating conditions the solenoid is maintained energized and the core is magnetically held in a raised position. In this position the upper end of the core is just beyond the upper end of the solenoid and thus through the link 74, holds the actuating finger 65 in a raised position within the cam block slot 69, this being 40 the position shown in Figs. 3 and 5. Hence the finger moves back and forth in the slot without doing any work as it is shifted by the reciprocating feed bar. In raised position it in no way interferes with proper feeding of the blanks A from 50 the magazine.

However, when abnormal conditions occur in the machine, the feed stop switch 88 is opened, the solenoid circuit is broken and the solenoid is thus de-energized. De-energizing of the solenoid 55 permits its core 78 to be drawn in by the solenoid spring 83 and finger 65 falls into its lowermost or depressed position, as shown in Figs. 6 and 7. If the finger is in a forward position (Fig. 7) when this happens, its hook end 68 drops down 60 over the lug 72 of the cam block 58. If the finger is at the opposite or back end of its stroke as shown in Fig. 5 when it falls down it will, on the next forward stroke, ride over the lug 72.

In any event the finger on the return stroke, 65 i. e., when the feed bar moves back, engages with the cam block lug and draws the cam block back toward the left, Fig. 6 showing the end of the backward movement. It is this action which shifts the cam surface 57 under the roller 56 so 70 that the roller rides up on the high or raised portion of the cam surface. The arms 51 and that portion of the blanks in the magazine supported thereon are thus raised.

75 This is the movement which lifts the blanks out

of the path of travel of the feed bar dog 31 and prevents further feeding of new blanks from the magazine, while the feed bar continues to reciprocate with the other moving parts of the machine. 5 Feeding of the blanks is thus stopped without stopping the operation of the machine and hence any blanks already in the machine will continue along their regular normal path of travel until discharged. 10 When it is desired to resume feeding of the blanks from the magazine, the feed stop switch 88 is closed. This may be a manual or an automatic operation. Closing of the switch re-establishes the solenoid circuit and hence re-energizes the 15 solenoid. This raises the core 78 with a consequent raising of the finger 65 back into the position shown in Figs. 3 and 5. In such a position the finger, moving forward on a forward stroke of the feed bar, engages against the shoulder 71 20 of the cam block 58 as in Fig. 3. This slides the cam block forward into its normal position, as shown in Fig. 3.

The forward shifting of the cam block thus permits the arm roller 56 to ride back onto the lower portion of the cam surface 57. It is this movement of the roller which allows the arms 51 to fall into their normally lowered position. This releases the blanks in the magazine and they move down into engagement with the supporting 30 lugs 17 where they are again in proper position for feeding by the feed bar dog 31.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being 40 merely a preferred embodiment thereof.

I claim:

1. In a feeding mechanism for can body blanks or the like, the combination of support means for a stack of blanks, feeding devices for feeding the supported blanks individually from the bottom of the stack, and instrumentalities engageable beneath the stack of blanks and adapted to elevate the same from the path of travel of the feeding devices when it is desired to prevent further feeding of the blanks without disturbing the normal position and operation of the feeding devices.

2. In a feeding mechanism for can body blanks or the like, the combination of support means for a stack of blanks, feeding devices for feeding the supported blanks individually from the bottom of the stack, a movable arm extending under the supported stack of blanks, and arm actuating elements for shifting said arm, said actuating elements being adapted to elevate said arm and the stack of blanks above said support out of the path of travel of said feeding devices when desired, whereby continued feeding of the blanks may be prevented without interfering with the continued operation of the feeding devices.

3. In a feeding mechanism for can body blanks or the like, the combination of a magazine for retaining a stack of blanks, a reciprocating feed bar adjacent said magazine for individually removing the blanks from the bottom of the stack, a movable arm having one end disposed under said stack of blanks and adapted to engage and elevate the latter above the path of travel of the feed bar when desired, whereby to prevent fur-

ther feeding of blanks from the magazine without interfering with the continued operation of the feed bar.

4. In a feeding mechanism for can body blanks or the like, the combination of a magazine for retaining a stack of blanks, a reciprocating feed bar adjacent said magazine for individually removing the blanks from the bottom of the stack, a movable arm having one end disposed under said stack, a slideable cam on which said arm rests, and means cooperating with said feed bar for shifting said cam relative to said arm for actuating the latter to lift the stack of blanks above the path of travel of the feed bar when desired, whereby to prevent further feeding of blanks from the magazine without interfering with the continued operation of the feed bar.

5. In a feeding mechanism for can body blanks or the like, the combination of a magazine for retaining a stack of blanks, a reciprocating feed bar adjacent said magazine for individually removing the blanks from the bottom of the stack, a movable arm having one end disposed under said stack, a slideable cam on which said arm rests, a finger traveling with said feed bar and adapted to be moved relative to the cam, and devices operable to shift said finger into a position where it will engage and move said cam relative to said arm for actuating the arm to lift the stack of blanks above the path of travel of the feed bar when desired thereby preventing feeding of blanks from the magazine without interfering with the continued operation of the feed bar.

6. In a feeding mechanism for can body blanks or the like, the combination of a magazine for retaining a stack of blanks, a reciprocating feed bar adjacent said magazine for individually removing the blanks from the bottom of the stack, a movable arm having one end disposed under said stack, a slideable cam on which said arm rests, a finger traveling with said feed bar and adapted to be moved relative to the cam, and an electric solenoid connected with said finger and operable when desired for shifting said finger into a position where it will engage and move said cam relative to said arm thereby actuating the arm to lift the stack of blanks above the path of travel of the feed bar, whereby further feeding of blanks from the magazine will be prevented without interfering with the continued operations of the feed bar.

7. In a feeding mechanism for can body blanks or the like, the combination of a magazine for retaining a stack of blanks, a reciprocating feed bar adjacent said magazine for individually removing the blanks from the bottom of the stack, a movable arm having one end disposed under said stack, a slideable hollow cam on which said arm rests, said cam having an internal shoulder and an internal lug, a finger pivotally connected to said feed bar and having a hooked end adapted to be moved into and out of the cam adjacent the shoulder and lug therein, and devices operable at will for shifting said fingers into engagement with said cam shoulder or said cam lug for sliding the cam in one direction or an opposite direction along said arm, whereby to actuate the latter to lift the stack of blanks above the path of travel of the feed bar when abnormal conditions occur, whereby further feeding of blanks from the magazine will be prevented without interfering with the continued operations of the feed bar.

JUSTIN SIMPSON.
